UNITED STATES PATENT OFFICE.

GEORGE CHRISTENSON, OF NORTH PLAINFIELD, NEW JERSEY, ASSIGNOR TO JOHNS-MANVILLE, INCORPORATED, OF NEW YORK, N. Y., A CORPORATION OF NEW YORK.

SWAB AND PACKING FOR DEEP WELLS.

Application filed May 22, 1924. Serial No. 715,159.

To all whom it may concern:

Be it known that I, GEORGE CHRISTENSON, a citizen of the United States of America, and resident of North Plainfield, in the 5 county of Somerset and State of New Jersey, have invented new and useful Improvements in Swabs and Packings for Deep Wells, of which the following is a specification.

10. This invention relates to heavy-duty liquid driving plungers, lifting bailers or swabs, so-called, and to packings therefor, and particularly to swabs capable of operating under great pressures without disqualifying 15 mutilation of or injury to their packings by a mechanically imperfect cooperating interior cylindrical surface; for example, by the ordinary casing of a deep tubular well.
20. In one form of deep well practice, liquids are retrieved from great depths by swabbing or bailing, the tubular well casing serving as the cylinder of a lift pump during a long upward stroke of a fluid-tight 25 piston. Such a swab, bail or piston ordinarily comprises a weighted tubular stem connected to a wire hoisting cable, and provided with multiple packings intended to bridge the space between the stem and the 30 interior surface of the well casing. This function is not usually well performed in practice, because of the inherent difficulty of packing against great pressures the variable clearance space between the stem of 35 the swab and the rough and irregular wall of the casing. An opening through the swab controlled by a check valve (or an opening past the swab stem and collapsible packing cups) usually is relied upon to permit descent of the swab under gravity.

The pressures to which such swabs are subjected are very great; this and the often rough and broken surface of the well casing prevent ordinary packing devices from 45 proper effect; the customary devices are notoriously unreliable and inefficient, and lack durability to such an extent that a single stroke of the piston frequently destroys the packing element; a score or less of strokes without renewal of the packing elements is regarded as a satisfactory performance of the existing apparatus.

Objects, among others, of this invention are therefore to provide a lifting plunger 55 adapted to make a fluid tight connection

with the interior walls of a cylinder of variable and imperfect mechanical construction; to provide for doing this by means adapted to prolong the useful life of the plunger packing; to provide a swab packing 60 protected against mutilation by projections and irregularities of the interior walls of a well casing; and in general to improve the operative efficiency and durability of devices for purpose mentioned.

The invention will be explained in connection with one preferred form shown in the accompanying drawings, in which,—

Fig. 1 is a central vertical section in elevation of a well casing and swab;

Fig. 2 is an enlarged vertical sectional elevation of a protective cap, packing and calyx showing the relation of the parts; and

Fig. 3 is an enlarged elevation of an expansion-resisting protective cap for the packing element.

The well casing as shown may comprise the abutting pipe sections 1, 2, etc., exteriorly screw threaded for the usual couplings 3, but not necessarily contacting at their abutting ends, which are often marred and blurred. Such casings characteristically are rough, often dented, and seldom accurately cylindrical.

The bailer or swab shown may comprise a tubular stem 4, preferably screw threaded on its exterior surface throughout its length, having a tapered terminal nut 5 at one end of the stem and a protective retaining head 6 at the opposite end of the stem, one of these structures (as shown, the head 6) having annular surfaces to receive the seat 12, cage 9 and ball 11 of the usual check-valve controlling the central bore in stem 4. A terminal threaded lug 10 provides an attachment place for the usual swivelled hoisting cable coupling 8.

Stem 4 is of suitable length to provide seats for a sufficient number of expandable, relatively flexible packing cups or annuluses 15, their mounts and restraining elements.

In practice the swab is lowered or sunk into the well, by its own weight, liquid in 105 the well passing upward through the bore of the stem 4, past check valve 11, and through openings 13 in cage 9 into the well casing above the swab; when the swab is 110 hauled up within the casing by hoisting on

the cable, the superimposed column of liquid is lifted to the surface. It is obvious that the exterior attachments of stem 4 should be such as to pass the casing pipe joints and other obstructions, without leakage, or if deformed for this passage, to resume operative contact with the casing after passage. For these purposes the cups or annuluses 15 are preferably structures of rubber or rubber compounds adapted and mounted to bridge the clearance space between stem 4 and casing 1, 2 under circumstances permitting these packings to yield and protecting them from excessive abrasion and mutilation by the internal burrs and projections inevitably found in the well casing. In order to maintain continuity of liquid tight packing between the piston comprised of the swab and the cylinder 20 comprised of the casing, the swab is built up of elements comprising a sufficient number of the cups or annuluses 15 to insure operative sealing contact with the casing wall of one or more of them at any one time. The stem 4 for example, is provided with spaced seats 17 for a sufficient number of the annuluses 15, (each of which comprises a heel section 16, a median cylindrical portion, and a lip section 18), to insure the presence of one or more of the annuluses in a part of the casing with which good sealing contact is possible.

Such a sealing contact is provided to be made by making the cups, annuluses or packings of a structure materially capable of expansion by longitudinally and outwardly acting forces tending to hold the median region of these packings in tight flexible contact with the inner surface of the casing, despite variations due to lack of cylindric figure or the presence of local cavities or projections of minor sizes.

In order to provide for a reasonable wear only on these packings, it is desirable to provide that they shall not expand into the grosser cavities of the casing, such as the space between pipe sections at the couplings, and particularly to provide that the lips 18 shall be protected against expansion into locking contact with such cavities.

In the preferred construction, the seats 17 are the conical cavities of centrally bored calyx cups 14 engaging the stem 4 and positioned by lock-nuts 22. The heel sections 16 of the packing annuluses 15 fit the seat cavities 17 of the cups 14, and are each provided with an internal shoulder 21 for a tubular spacer 20. Above the shoulders 21, the packings 15 preferably have a tapered

internal cavity, Figs. 1 and 2. Under longitudinal or internal pressure or both, the packings 15 tend to expand except as restrained by the cups 14, or by restraining means 19 adapted to prevent radial expansion of the lip sections 18 of the said packings.

The restraining means 19 may comprise a metal thimble or cup centrally bored for stem 4, resting on each spacer 20, and held from longitudinal motion by said spacer and the lower face of one of the lock nuts 22. Whatever the particular form of the restraining thimble 19, its annular or other extremity 7 overlies the lip portions 18 of the packings 15, and prevents expansion of the upper edge of the packing into contact with the casing walls.

Preferably the restraining thimbles 19 are shaped as indicated in the drawings and are provided with flow openings 23. The upper restraining means of the series used may comprise an integral skirt 27, Fig. 1, of the head 6.

Each of the described metallic parts 6, 14, 19 is of sufficient diameter only to give free clearance in the well casing. Because of this, leakage of liquid past any of the series of packings is afforded a free path around the restraining structures 27, 7 or through the openings 23 to act upon the packings 15 longitudinally and internally to cause them to expand. But the lips 18 can not partake of this expansion, being restrained by the parts 7, 27, and are therefore protected from contact with cavities or internal projections of the casing. By these provisions, the swab as a whole is enabled to operate under great pressures with high efficiency against leakage, and with great durability of the expanding packings. When worn, the described structure enables new cups or annuluses 15 to be assembled rapidly.

I claim:

In a plunger for deep well pumps, the combination with a tubular stem of an expandable packing member having an exteriorly downwardly tapered heel portion secured to said stem, a median bearing portion, a free end upwardly tapered exteriorly and downwardly tapered interiorly, and means secured to said stem and adapted to restrain movement of the free end of the packing member when the latter is subjected to forces tending to expand it.

Signed by me at New York city this 17th day of May, 1924.

GEORGE CHRISTENSON.
